CLAIM

The ornamental design for a shaver, as shown and described.

DESCRIPTION

FIG. 1 is a front perspective view of a shaver showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The partially illustrated foil pattern is understood to continue throughout the surface bounded by the inner circle of the front end.
